(57) **CLAIM**

I claim the ornamental design for a utility knife, as shown and described.

DESCRIPTION

FIG. 1 is a bottom, right perspective view of a utility knife, embodying the new design;

FIG. 2 is a top, left perspective view of the claimed design of FIG. 1;

FIG. 3 is a right side view of the claimed design of FIG. 1;

FIG. 4 is a left side view of the claimed design of FIG. 1;

FIG. 5 is a top view of the claimed design of FIG. 1;

FIG. 6 is a bottom view of the claimed design of FIG. 1;

FIG. 7 is a rear view of the claimed design of FIG. 1;

FIG. 8 is a front view of the claimed design of FIG. 1;

FIG. 9 is a cross-section view of the claimed design of FIG. 1 taken along line 9-9 in FIG. 4;

FIG. 10 is a bottom, right perspective view of the utility knife of FIG. 1, but illustrated using a wire frame line technique;

FIG. 11 is a top, left perspective view of the claimed design of FIG. 10;

FIG. 12 is a right side view of the claimed design of FIG. 10;

FIG. 13 is a left side view of the claimed design of FIG. 10;

FIG. 14 is a top view of the claimed design of FIG. 10;

FIG. 15 is a bottom view of the claimed design of FIG. 10;

FIG. 16 is a rear view of the claimed design of FIG. 10;

FIG. 17 is a front view of the claimed design of FIG. 10; and,

FIG. 18 is a cross-section view of the claimed design of FIG. 10 taken along line 18-18 in FIG. 13.

The broken lines depict portions of the utility knife in which the design is embodied that form no part of the claimed design.
